Primary Examiner—Stella Reid*Assistant Examiner*—G Andoll*Attorney, Agent, or Firm*—Marshall A. Lerner, Esq; Bradford E. Mattes, Esq; Kleinberg & Lerner, LLP[57] **CLAIM**

The ornamental design for a shoe upper, as shown and described.

DESCRIPTION

FIG. 1 is a perspective view of the front, left and top of a shoe upper showing my new design;

FIG. 2 is a left side elevational view thereof;

FIG. 3 is a right side elevational view thereof;

FIG. 4 is a top plan view thereof;

FIG. 5 is a front side elevational view thereof; and,

FIG. 6 is a rear elevational view.

The broken line showing the sole in the figures is for illustrative purposes only and forms no part of the claimed design.
